CLAIM

The ornamental design for a camera housing assembly, as shown and described.

DESCRIPTION

FIG. 1 is a first top perspective view of a camera housing assembly showing our new design;

FIG. 2 is a second top perspective view of the design of FIG. 1;

FIG. 3 is a right side view of the design of FIG. 1;

FIG. 4 is a left side view of the design of FIG. 1;

FIG. 5 is rear side view of the design of FIG. 1;

FIG. 6 is a front side view of the design of FIG. 1;

FIG. 7 is a top-down plan view of the design of FIG. 1; and,

FIG. 8 is a bottom-up plan view of the design of FIG. 1.

The broken line disclosure forms no part of the claimed design.

1 Claim, 4 Drawing Sheets
